CLAIM

I claim the ornamental design for a container for a string used on a weed eater, as shown and described.

DESCRIPTION

FIG. 1 is a front, top and side perspective view of the container for a string used on a weed eater embodying the design of the present invention.

FIG. 2 is a side elevational view thereof.

FIG. 3 is a side elevational view thereof.

FIG. 4 is a top plan view thereof.

FIG. 5 is a bottom view thereof.

FIG. 6 is an end elevational view thereof; and,

FIG. 7 is an end elevational view thereof.

In use, the container is mounted on the handle of the weed eater between the proximal and distal ends of the handle.
